UNITED STATES PATENT OFFICE.

BERNARD GRANVILLE, OF PROVIDENCE, RHODE ISLAND, ASSIGNOR TO THE MOSSBERG & GRANVILLE MANUFACTURING COMPANY, OF SAME PLACE.

TYPE-WRITER.

SPECIFICATION forming part of Letters Patent No. 672,849, dated April 23, 1901.

Original application filed February 5, 1900, Serial No. 4,029. Divided and this application filed July 2, 1900. Serial No. 22,328. (No model.)

To all whom it may concern:

Be it known that I, BERNARD GRANVILLE, a citizen of the United States, residing at Providence, Rhode Island, have invented certain new and useful Improvements in Type-Writers, of which the following is a specification.

My invention is an improvement upon that form of type-writer disclosed in Letters Patent of the United States granted me October 27, 1896, No. 570,433, and my present case is a division of that filed by me in the United States Patent Office February 5, 1900, Serial No. 4,029.

In the present machine I have provided means whereby a portion of the printing mechanism, in this instance the type-bars, may be shifted and set in position for printing either upper or lower case, and from either position the parts may be temporarily shifted into the other position when it is desired to print a comparatively small number of letters from the other case type.

In the drawings, Figure 1 is a plan view of the machine, the paper-carriage and other parts being omitted. Fig. 2 is a back view with the paper-carriage and other parts omitted. Fig. 3 is a part side elevation and partly a sectional elevation of the machine with unnecessary parts omitted. The carriage is omitted and the parts relating to the escapement are also omitted, the present case being limited to the type-bar action. Fig. 4 is a detail view of the dividing-comb for the type-bars.

In this improved machine the type-bars converge and are guided to the printing-point by converging guide-plates *a*, carried on a cradle-frame *b*, pivoted at *c* to the side frames of the machine, these parts being similar to those in the machine shown in the patent referred to. The type-bars are operated from the key-levers *d*, only a few of which are shown in the drawings, through the bell-crank levers *e* and the links *f*. Only two of these type-bars 60 are shown for convenience of illustration in Fig. 1. I have deemed it sufficient to show the platen diagrammatically in Fig. 3 and in plan view in Fig. 1 at X without showing the details relating thereto.

In order to do lower-case printing, the rear end of the cradle-frame, with the converging guide walls or sides, is in the lowest position in relation to the printing-point, and they form a guide-box which rests in its lowest position by gravity. A spring *q*, connected to the frame at *q'*, tends through a series of connections to raise the cradle-frame into its uppermost position for printing caps; but when lower-case printing is to be done the cradle-frame is relieved from the power of this spring 60 and the cradle-frame is allowed to rest in the lowest position by gravity.

Arms *k* and *m* on a square shaft *l*, journaled in the side frames, are connected by a link *o*, having a forked end 80, to a depending arm *p* of the cradle-frame. The spring *q*, pulling on the arm *m* of the square shaft, will push the fork 80, and thus lift the cradle-frame for upper-case printing, and in order to do lower-case printing the pull of the spring 70 *q* is withdrawn from the cradle-frame by a locking-lever *i*, which is pivoted to the frame and has an arm *j* to bear on the arm *k* of the square shaft, and when this locking-lever is set the link *o*, with the fork 80, is drawn forward and the cradle-frame is allowed to drop by gravity for lower-case printing. The locking-lever *i* is held in this position for lower-case printing by the spring *n*, connected therewith and with the frame. In order to change 80 from lower to upper case or cap printing, the cradle-frame *b* is tilted upwardly in the direction of arrow 61, Fig. 3, by means of a key *g*, the lever of which is connected by an adjustable link *h* with the depending arm 85 *p* of the cradle-frame. When this key is depressed, the cradle-frame is tilted, so that the converging guide-plates *a* are raised, and the type-bars will then be guided to present the upper-case or cap type to the 90 printing-point. In order to continue printing upper-case characters, the locking-lever *i* is turned by moving its upper end to the right in Fig. 3 to release the arm *k*, and then the spring *q*, connected to the main frame and to 95 the arm *m*, exerts its force to tilt the cradle-frame upwardly and hold it in this position until it is desired to resume the printing of

lower-case letters, at which time the locking-lever is moved to the position shown in Fig. 3, which, through the described connections, will withdraw the force of spring *q* and allow the cradle-frame to tilt downwardly by gravity. If during the time that the machine is set for upper-case printing (at which time, as above set forth, the frame is held up by the spring *q* and the locking-lever *i* is out of action) it is desired to print one or more small letters, a key *r* is depressed. The lever of this key is connected with the square shaft *l*, and, as shown, will when depressed rock the square shaft and withdraw the power of the spring *q*, thus allowing gravity to draw the cradle-frame down, holding it so as long as key *r* is held depressed. When key *r* is released, the spring *q* lifts the cradle-frame again for upper-case printing.

20 It will be seen from the above that the machine can be set to print continuously either upper or lower case, and also that when set for either case type printing of one or more letters of the other case may be accomplished by depressing a key.

The locking-lever in the present machine holds the lower-case type in line with the printing-point instead of the upper-case type.

The guide-box, composed of the converging 30 guide-plates for directing the type to the printing-point, is pivoted to the cradle-frame at 49 and is held normally up by springs 50, a stop 51 determining this upward position. When it is desired to examine the printing or 35 the last character printed, this box may be moved downwardly at its rear end, and for this purpose an arm 52 is connected to the guide-box, and a lever 53, engaging this arm, is operated from the keyboard by a link 54, 40 connected to one of the key-levers. In the present instance I utilize the carriage-unlocking lever 31 for operating the guide-box, said lever and its connections being fully described in my original application, of which 45 this case is a division.

The key for depressing the guide-box on the cradle-frame to reveal the printing (the unlocking-key 31 in this instance) is located directly adjacent to the lower-case key, so 50 that by operating both of these keys simultaneously the guide-box can be depressed to its maximum extent to reveal the printing. A dividing-comb 83 is employed having pins 83' to divide the series of type-bars into groups 55 of three, four, or more, and by this comb the type-bar action is rendered quiet and easy in operation. This comb prevents a large number of type-bars being moved laterally when any one is operated, as the movement of one 60 type-bar will simply shift laterally those of its own small group. The comb comprises upper and lower plates, Fig. 4, for the upper and lower rows of type-bars. The comb is attached to a suitable part of the cradle-frame.

65 I claim as my invention—

1. In combination, in a type-writer, the cradle-frame, converging type-bars carried there-

by, means for setting the cradle-frame to print either lower or upper case, means for temporarily shifting the parts from lower to upper 70 case printing and means for temporarily shifting the parts from upper to lower case printing, substantially as described.

2. In combination in a type-writer, a cradle-frame, converging type-bars carried thereby, 75 means for setting the cradle-frame for upper-case printing and a key for changing temporarily from upper to lower case printing, substantially as described.

3. In combination in a type-writer, a cradle-frame, converging type-bars carried thereby, 80 means for holding the cradle-frame up, means for temporarily shifting the cradle-frame to its lower position, means for throwing the holding means out of action and means for 85 temporarily shifting the cradle-frame from its lower to its upper position, substantially as described.

4. In combination, printing mechanism, a spring for holding a portion of the same in 90 position to print one set of characters, and a key for relieving the force of said spring to allow the printing to change by gravity from one set to another, substantially as described.

5. In combination, printing mechanism including a cradle-frame and converging type-bars, a spring for holding a portion of the same in position to print one set of characters, a key acting in opposition to the spring to allow the printing mechanism to shift by 95 gravity from one set of characters to another, means acting in opposition to the spring for setting the parts to print said other set of characters, and means for temporarily shifting from said other set of characters to the 100 first set of characters, substantially as described.

6. In combination, the printing mechanism having a shifting portion, a spring for holding said shifting portion in one position, 110 means for relieving the force of the spring to allow the said portion to shift by gravity, a key for moving the said portion in opposition to the force of gravity and means for temporarily relieving the said portion from 115 the force of the spring, substantially as described.

7. In combination, the cradle-frame, a spring for holding the same in its upper position, a lever for relieving the force of the spring 120 from the cradle-frame allowing the same to fall by gravity, a key for temporarily raising the cradle-frame and a second key for temporarily relieving the pressure of the spring, substantially as described.

8. In combination, a cradle-frame, a spring, a loose connection between the spring and cradle-frame, means for withdrawing the pressure of the spring, and means for shifting the cradle-frame when the spring-pressure is 130 withdrawn, substantially as described.

9. In combination, the cradle-frame, a spring for applying pressure thereto, a loose connection between the spring and cradle-

frame, a lever *i* for permanently withdrawing the pressure of the spring and a key-lever for temporarily withdrawing the pressure of the spring, substantially as described.

5 10. In combination, the cradle-frame having a depending arm, a spring, a fork connected loosely with the depending arm, a rock-shaft *l*, connections between said rock-shaft and fork, said spring being joined to said connections, a lever *k* on the rock-shaft, means for setting lever *k*, a key-lever for turning the rock-shaft and a key-lever connected to the depending arm for raising the cradle-frame, substantially as described.

15 11. In combination, the cradle-frame, a spring, a loose connection between the spring and the cradle-frame, means for withdrawing the pressure of the spring and means for moving the cradle-frame in the same direction in 20 which the spring normally tends to move it, the said loose connection allowing the latter action to take place, substantially as described.

25 12. In combination with converging type-bars, a vertically-movable guide-box and means extending to the keyboard to depress said guide-box to reveal the printing, substantially as described.

30 13. In combination, the converging type-bars, the guide-box, means for changing from one case type to another by shifting the guide-box and connections extending to the keyboard for giving the guide-box an independ-

ent movement to reveal the printing, substantially as described.

14. In combination, the converging type-bars, the guide-box, a key with connections for lowering the guide-box in changing from one case type to another and a key with connections for giving the guide-box an additional lowering movement, substantially as described.

40 15. In combination, the converging type-bars, the guide-box, a key with connections for lowering the guide-box in changing from one case type to another and a key with connections for giving the guide-box an additional lowering movement, said keys being adjacent to each other, substantially as described.

45 16. In combination with the converging type-bars, a comb for dividing said bars into groups, each group comprising several bars which pass through the space between two of the bars of the comb, substantially as described.

50 17. In combination the upper and lower rows of type-bars and the upper and lower combs for dividing the type-bars.

55 In testimony whereof I affix my signature in presence of two witnesses.

BERNARD GRANVILLE.
